UNITED STATES PATENT OFFICE.

WALKER G. BROWNE, OF ATLANTA, GEORGIA, ASSIGNOR TO THE UNITED STATES AUTOMATIC WATER CUT-OFF COMPANY, OF GEORGIA.

AUTOMATIC CUT-OFF.

SPECIFICATION forming part of Letters Patent No. 380,987, dated April 10, 1888.

Application filed March 15, 1887. Serial No. 231,039. (No model.)

To all whom it may concern:

Be it known that I, WALKER G. BROWNE, a citizen of the United States, residing at Atlanta, in the county of Fulton and State of Georgia, have invented a new and useful Automatic Cut-Off for Water-Pipes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to the automatic cutting off of the flow of water in water-pipes and draining the water beyond the cut-off valve from them on the lowering of the temperature, to prevent the freezing of the water in the pipes; and it consists of a self-closing stop and waste valve and restraining mechanism, with compound plate to automatically release the same, and draining-valves that are operated by the water that is discharged by the stop and waste valve, as will be hereinafter fully described.

In the accompanying drawings, Figure 1 is a side view, partly in section, showing the compound plates, restraining catch and rod, and the valve and the chain for opening the valve. Fig. 2 is a cross-section on line $x-x$, Fig. 1. Fig. 3 is an enlarged view of the restraining catch, lever, and rod. Fig. 4 is an end view of the lever. Fig. 5 is a view of my device as used in practice in a basement, showing a stop and waste valve and actuating mechanism, and draining-valves, and bucket-weights, by which the valves are opened whenever the buckets are filled with water from the stop and waste valve. Fig. 6 is an enlarged sectional view of the pipes by which the bucket-weights on the draining-valves are filled, and having a contracted discharge-opening, by reason of which the water may be made to flow through several openings at the same time.

In the figures, like reference-marks referring to like parts, A is a water-supply pipe, on which is a stop and waste valve, B, having lever b and weight C. The valve, as shown, is open and allows the water to flow through it, and the weight C is held in this position by the engagement of the catch d on the lever D

with the restraining-rod c , Figs. 1 and 3. The restraining-rod is caused, on the raising of the weight C by the chain c' , to engage with the catch d by the spring d' , which bears against one side of the opening in the base-plate, through which the restraining-rod passes.

The lever D is pivoted on the pine in an upward projection on the base-plate E, and the end opposite the catch d is held down by contact with the catch f on the compound plate F. The compound plate, being constructed of strips of metal having different expansive qualities, will by the contraction produced by cold release the end of the lever D with which it is in contact and allow the weight to pull the catch down sufficiently to cause the restraining-rod to slip off the catch and allow the weight to close the valve.

It will be observed by Figs. 1 and 3 that the downward motion of the catch carries it backwardly and forcibly withdraws it from the hole in the restraining-rod c , the rod being prevented from following the catch by contact with the lever. When the weight C drops, it will carry the restraining-rod with it, by reason of which the spring d' will not bear against the base-plate, but will allow the lever and catch to fall to the position shown, where they will be held by the compound plate whenever a return of a higher temperature shall have expanded them, after which, the weight C having been raised by the chain, the catch d will engage with the restraining-rod and hold it, thus allowing the water to flow.

The adjusting-screw f' in the compound plate, Fig. 1, is for the purpose of adjusting the catch f on the free end of the compound plate, to cause it to release the lever D on the falling of the temperature to the degree at which it is desired to cut off the water. As the lever D will not be held by the compound plate in the position in which it will sustain the weight and hold the valve open until a rise of temperature shall have caused it to engage with the lever, the opening of the valve by raising the weight will not allow the water to flow longer than the valve is held open by means other than the lever D.

The stopping of the forward flow of water by the stop and waste valve B will cause the backward flow and discharge of such water as

shall have passed through the valve and is still in the pipes and at a higher level than this outlet. It is, however, often found that exposed portions of the pipe are at a lower level than the stop and waste valve, or otherwise prevented from draining backwardly through that valve. Such portions of the pipes I drain by attaching waste-valves G and H, as shown in Fig. 5, to the lowest or any desirable parts of the pipes. To the levers of these waste-valves are attached vessels J and K, of sufficient size to contain enough weight of water to open these valves. On the closing of the valve B whatever water shall remain in the pipe A above that level will be discharged through the waste-port in the valve B into the pipe L, through which it will flow and discharge a portion into the vessel J and a portion into the vessel K, the outlets or other portions of the pipes being contracted, as shown in Fig. 6, to prevent the discharge of all of the water at one outlet. It is obvious that in some instances only one of the supplemental valves need be used, while in others more than two might be required; but I have shown this system of pipes as applied to two openings, as I believe it sufficiently illustrates the principle of that part of my invention. The compound plates shown in Figs 1, 2, and 3 are similar to those shown in my Patent No. 351,093, of October 9, 1886, except that instead of hinges to join the central pair of plates I use U-shaped strips of metal, g, the strips 1 4 5 8 being of a metal which contracts or expands to a greater extent as the temperature rises or falls than those marked 2 3 6 7. On the contracting by cold of plate 1 the com-

pound plate composed of plates 1 and 2 will bend or bow in the direction indicated by the arrow x. The compound plates composed of plates 3 and 4 and 5 and 6 will form an ellipse, opening the U-shaped springs S S. The upper ends of the compound plates are firmly fastened nearly parallel to sides of the upper spring. As these sides of this spring are opened and the angle which they make with each other becomes greater, so will the angle or distance between the lower ends of compound plates composed of plates 1 2 and 7 8 become greater. As the end of compound plate 1 2 is fixed, the plate 7 8 must do all the moving which is done in the direction of the arrow Z; but I believe that other forms of compound plate might be used without a departure from the principle of this invention. 55

Having thus described my invention, what I claim as new, and desire to secure by Letters Patent of the United States, is—

1. The combination of the compound plates 1 2 3 4, the support to which they are fastened, the U-shaped elastic spring joining said plates, the spring f, the screw f', the lever D, the bolt e, the catch d, the rod c, and the spring d', substantially as set forth. 6c

2. The compound plates 1 2 3 4, the lever D, the catch d, and the rod c, in combination with the weight C, the lever b, valve B, and chain c'. 65

In testimony whereof I affix my signature in presence of two witnesses.

WALKER G. BROWNE.
